[57] **CLAIM**

The ornamental design for a swab box, as shown and described.

DESCRIPTION

FIG. 1 is a plan view of a swab box showing my new design;

FIG. 2 is a front elevational view thereof;

FIG. 3 is a right-side elevational view thereof, the left-side elevational view being a mirror image;

FIG. 4 is a bottom view thereof;

FIG. 5 is a rear elevational view; and

FIG. 6 is a section along line 6—6 of FIG. 2, the section in the opposite direction being a mirror image.

6 FIG.1
